SIGNAL DEVICE

Lloyd Rittenhouse, Honeoye Falls, N. Y., assignor
to The A. E. Rittenhouse Co., Inc., Honeoye
Falls, N. Y., a corporation of New York

Application November 18, 1937, Serial No. 175,296

6 Claims. (Cl. 177—7)

This invention relates to a signal device, of the general type used in homes, to take the place of the conventional door bell and give an indication when someone is at a door, or for other similar purposes, which include electrically operated striker operating mechanism in conjunction with a vibratable plate or chime that is struck and gives the desired signal upon the closing of an electric circuit to the electro-magnet or other operating means.

One object of the invention is to afford a simple and practical design for removably supporting a vibratable plate or chime bar so that the latter can be packed and shipped separately, and quickly assembled on its supporting instrumentalities when the signal is installed.

A further purpose of the invention is to afford a simple construction that can be economically manufactured, is efficient and dependable in its operation, and will permit the quick and ready positioning or removal of the vibratable plate or chime bar upon its supporting means.

Another object of the invention is to afford a compact arrangement that is neat and ornate in its appearance and which can be conveniently secured in place on a wall or suitable support.

To these and other ends, the invention consists in the construction and arrangement of parts that will appear clearly from the following description when read in conjunction with the accompanying drawing, the novel features being pointed out in the claims following the specification.

In the drawing:

Fig. 1 is a plan view of a signal device constructed in accordance with one embodiment of the invention;

Fig. 2 is a front elevation, and

Fig. 3 is a vertical sectional view on the line 3—3 of Fig. 2.

Referring more particularly to the drawing in which like reference numerals refer to the same parts throughout the several views, 1 designates a housing, closed at the bottom and open at the top as shown, affording a resonance chamber within which is located electrically operated striker operating means, preferably in the form of an electro-magnet 2 and a vertically movable striker 3, which moves upwardly under the impulse of the electro-magnet and strikes a chime plate or bar to give the required signal.

At the top of the housing 1, secured to one side thereof, is a supporting plate 4, which may be attached in any desired manner to a wall or base, and which is provided with terminals or binding

posts 5 from which conductors lead to the electro-magnet 2.

The supporting plate 4 is permanently attached to the housing 1 by spot-welding or soldering, and when secured to a wall or support, constitutes the means for holding the entire unit in operative position. The vibratable plate or chime bar is indicated at 6 and includes transverse openings 7 located nearer to the rear edge of the plate than the front edge, as shown in Fig. 3. 10

This plate is removably positionable upon a pair of arms secured to the supporting plate 4 and located at the ends thereof. Each of these supporting arms includes a top horizontal portion 8 that overlies the rear portion and rear edge of 15 the vibratable plate 6, a horizontal portion 9 that underlies the front part of the vibratable plate 6 and extends toward its forward edge, and a vertical portion 10 that extends through the opening 7 in the plate. The supporting arms are 20 preferably encased in suitable tubes 11 of rubber, and the openings 1 are made sufficiently larger than the diameter of the supporting arms so that the vibratable plate can be readily tilted from the position shown in Fig. 3 toward a vertical position to remove it from the supporting arms. 25

When in position, the front or wider portion of the vibratable plate rests with its weight upon the underlying horizontal portions 9 of the arms 30 and is thus held against accidental removal, though it can be quickly and easily displaced when necessary. This has the advantage of permitting the device to be shipped with the elongated vibratable plate or bar separate from the 35 other parts, thus making a less bulky and more convenient package for shipping, and when the device is installed, the vibratable plate can instantly be assembled in position on the supporting arms. 40

In order to maintain the supporting arms on the supporting plate 4, the arms are extended through openings in the plate 4 and have downwardly depending portions 12 which lie adjacent to the rear surface of the plate 4 and are fixedly secured thereto by spot-welding, soldering, or in any other convenient manner. 45

While the invention has been described with reference to a particular embodiment, it is not restricted to the details herein disclosed, and this application is intended to cover any other modifications or departures that may come within the purposes of the improvement or the scope of the following claims. 50

I claim:

1. In a signal device, the combination with
striker operating means, and a vibratable plate
having transverse openings therein closer to one
edge, of supporting arms comprising horizontal
portions which overlie the rear part and rear edge
of the vibratable plate, horizontal portions which
underlie the front part of the plate and extend
toward its front edge, and vertical connecting
portions which extend through said transverse
openings in the plate, the openings being suffi-
ciently larger than the supporting arms to permit
ready removal or positioning of the plate, and a
striker arranged to engage said vibratable plate
adjacent to a line passing through said openings.
2. In a signal device, the combination with
striker operating means, of a vibratable plate
having openings closer to the rear edge than to
the front edge, a supporting plate, supporting
arms carried by said plate and having horizon-
tal portions which overlie the rear part of the vi-
bratable plate, horizontal portions which underlie
the front part of the plate, and connecting
vertical portions which extend through said open-
ings in the plate, the openings being sufficiently
larger than the supporting arms to permit ready
removal or positioning of the plate with relation
thereto.
3. In a signal device, the combination with
striker operating means, and a vibratable plate
having openings therein, a supporting plate, sup-
porting arms secured thereto and comprising hori-
zontal portions which overlie said plate, hori-
zontal portions which underlie said plate, and
vertical portions connecting said horizontal por-
tions and extending through said openings in the
vibratable plate, said openings being substan-
tially larger than the said connecting portions of
the supporting arms.
4. In a signal device, the combination with

striker operating means and a supporting plate
located thereabove, of supporting arms secured to
said supporting plate and including upper and
lower horizontal portions and connecting vertical
portions, and a vibratable plate removably posi-
tionable upon the lower horizontal portions of
said supporting arms, said plate including open-
ings of greater diameter than the thickness of the
supporting arms and located closer to one edge of
the plate than the other whereby the plate is re-
movably positionable on the supporting arms.

5

10

5. In a signal device, the combination with a
vertically arranged elongated housing open at
the top and striker operating means located with-
in the housing, of a vertically disposed supporting
plate secured to one side of the housing and ex-
tending above and laterally beyond the housing, a
vibratable plate arranged horizontally above said
open top of the housing and extending therebe-
yond, and supporting arms located at the ends of
20

20

said supporting plate, the vibratable plate being
positionable horizontally on said supporting arms
and removable therefrom, and a striker movable
through said open top of the housing and engage-
able with said vibratable plate.

25

6. In a signal device, the combination with
striker operating means and a supporting verti-
cally arranged plate located thereabove and to
one side, of supporting arms secured to said sup-
porting plate and including upper and lower hor-
30

30

izontal portions and connecting vertical portions,
and a vibratable plate removably positionable
upon the lower horizontal portions of said sup-
porting arms, said plate including openings of
greater diameter than the thickness of the sup-
35

35

porting arms and located closer to one edge of
the plate than to the other whereby the plate is
removably positionable on the supporting arms.

LLOYD RITTENHOUSE. 40
